UNITED STATES PATENT OFFICE.

HOWARD HUNT, OF MONROE, WISCONSIN.

WAGON-BRAKE.

SPECIFICATION forming part of Letters Patent No. 394,365, dated December 11, 1888.

Application filed November 16, 1886. Renewed August 25, 1888. Serial No. 283,793. (No model.)

To all whom it may concern:

Be it known that I, HOWARD HUNT, a citizen of the United States, and a resident of Monroe, in the county of Green and State of 5 Wisconsin, have invented certain new and useful Improvements in Wagon-Brakes; and I do declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 Figure 1 of the drawings is a representation of a bottom plan view. Fig. 2 is a vertical longitudinal section on the line *x* *x*, Fig. 1. Fig. 3 is a detail view, partly in section, of one of the brake-shoes.

20 My invention relates to automatic wagon-brakes; and it consists in the construction and novel combination of parts, as herein-after described and claimed.

25 Referring by letter to the accompanying drawings, A designates the running-gear of a wagon, which may be of any ordinary construction, except as to novel features described further on.

30 B is the front axle, C the rear axle, and D the reach.

E E are the front hounds, F the hind hounds, and G H the front wheels of the running-gear.

35 I is the tongue or pole, which is slotted transversely through at K L M to receive the transverse bolt-rod N, by which it is held in place between the extensions or arms of the front hounds.

40 P is a spiral or coil spring, which is connected at one end to the tongue or pole I by a casting, Q, or in any other suitable manner, and at the other end said spiral or coil spring is connected to the front bolster or sand-board, R, and serves to assist in supporting 45 the weight of the pole and keeping it from the horses' necks.

At their rear ends the arms of the front hounds are connected by a transverse bar, S, to the lower face of which the brake-levers 50 T U are fulcrumed, the fulcrum-points being near the outer ends of said transverse bar S. Loops V V, connected to the transverse bar S, surround the brake-levers T U near their inner ends and limit the movement down-

ward of said brake-levers. At their outer 55 ends the brake-levers T U are provided with brake-shoes V' V', which are designed to brake the front wheels of the wagon. The brake-shoes V' V' are provided on their convex edges with curved tangential metal 60 scrapers W, which, when the brakes are applied, engage the tires of the front wheels and scrape the mud therefrom and prevent it from reaching the brake-shoes. At their inner ends the brake-levers are connected to 65 the sliding tongue or pole by a forked rod, X. When the team draws upon the tongue, the brakes are thrown off the front wheels; but when descending an incline the weight of the wagon, pressing forward on the tongue, 70 applies the brakes, and the greater the load on the wagon the greater will be the pressure on the brakes. The coil-spring also assists the horses in applying the brakes, for as soon as the horses cease to draw upon the 75 tongue the spring retracts it and of itself will apply the brakes with considerable force.

Having described this invention, what I claim, and desire to secure by Letters Patent, is—

80 1. The combination, with the running-gear of a wagon provided with the sliding tongue and the transverse bar secured to the reach and front hounds in rear of the front wheels, of the brake-levers, the brake-shoes, the 85 spring connecting the sliding tongue to the front bolster, and the forked rod connecting the brake-levers and sliding tongue, substantially as specified.

2. The combination, with the brake-levers 90 and the sliding tongue connected therewith, of the spring connecting the sliding tongue to the running-gear of the wagon, whereby when the draft on the tongue is relieved the brake is applied, substantially as specified. 95

3. The combination, with the running-gear of a wagon, of the sliding tongue and brake-levers and connections, the brake-shoes, and the curved tangential scrapers W, secured to the edges of said shoes, substantially as specified. 100

In testimony whereof I affix my signature in presence of two witnesses.

HOWARD HUNT.
